[57] ABSTRACT

Apparatus for supporting a plurality of members in spaced relation including a first base, a bore formed in the first base, a second base, a bore formed in the second base, and an elongated pin slidably secured within the bores of the first and second bases to support them in axially disposed spaced relationship. Each of the bases is designed to support a member, e. g., a wig or hair piece, thereon. The elongated pin is provided with at least one tapered end and adapted to be passed through the member supported.

APPARATUS FOR SUPPORTING A PLURALITY OF MEMBERS

BACKGROUND OF THE INVENTION

This invention relates generally to the field of support devices. In particular, this invention relates to apparatus for supporting a plurality of intersticed members, e. g., wigs or hairpieces, in spaced stacked relationship.

Storage of all types of goods has been a problem of manufacturers, wholesalers, retailers and consumers down through the years. This problem has been particularly vexing when the articles to be stored must be separated from adjacent articles in order to preserve their appearance or structure. In such instances, the package for support means must be structurally capable of supporting the goods while at the same time the support means must be light in weight and not overly bulky.

Typical of goods which must be stored individually in order to preserve their structure and shape are wigs or hairpieces. The acceptance of the wig as a standard element of feminine fashion and the growth of their popularity to the extent that many feminine wardrobes include a plurality of wigs for different occasions, has resulted in storage problems for the average wig owner which parallel those of the average wig retailer and wholesaler. Specifically, in order to keep their set, wigs and hairpieces must be stored in such a manner as to maintain their hair surfaces out of contact with other adjacent surfaces.

SUMMARY OF THE INVENTION

It is an object of the present invention, therefore, to provide an apparatus for supporting a plurality of members in spaced relation.

A further object of the invention is to provide an apparatus for supporting a plurality of members in spaced relation such that the surfaces of the members are out of contact with any surface but the surface of their specific support structure.

These objects and others which will become evident to those skilled in this art from a reading of the following detailed description are achieved by the support structure of the present invention, one embodiment of which may include a first base, bore means formed in the first base, a second base, bore means formed in the second base, and an elongated pin having a first end and a second end, the first end for being slidably received within the bore means in the first base, the second end for being slidably received within the bore means in the second base, the pin for positioning the first and second bases in spaced relation, and wherein the first and second bases are each adapted to support a member, e.g., a wig, thereon.

BRIEF DESCRIPTION OF THE DRAWINGS

A more complete understanding of the present invention may be had from the following description, particularly when read in the light of the accompanying drawings, wherein:

FIG. 1 is an elevational view of a support structure according to the invention which is being utilized to support a plurality of wigs or hairpieces, the wigs or hairpieces being shown in phantom line;

FIG. 2 is a cross-sectional elevational view of apparatus according to the present invention showing an apparatus for supporting two members;

FIGS. 3a, b and c are cross-sectional views of the top rod, elongated pin and base rod utilized in the apparatus of FIG. 2, respectively.

DETAILED DESCRIPTION

Referring therefore to FIG. 1, an apparatus according to the present invention is shown and designated generally by the reference numeral 10. Specifically, apparatus 10 comprises a first base 12, a second base 14, a third base 15 and a fourth base 16. Second base 14 is disposed above and spaced from first base 12 by a vertically axially extending first elongated pin 18. Similarly, third base 15 is spaced axially above second base 14 by a second elongated pin 19. Fourth base 16 is disposed vertically axially above third base 15 by a third elongated pin 20. Each of bases 12, 14, 15 and 16 is shown supporting a wig or hairpiece, the wigs and hairpieces being shown in FIG. 1 in phantom line.

The structures of apparatus according to the present invention may best be seen with reference to FIGS. 2 and 3. Specifically, FIG. 2 shows an apparatus such as apparatus 10 but having only first and second bases. However, for purposes of description, like structure will be represented by like reference numerals and therefore, first base of the apparatus of FIG. 2 is designated by reference numeral 12, the second base of the apparatus of FIG. 2 is designated by reference numeral 14 and the elongated pin which spaces first and second bases 12 and 14 and vertical spaced relationship is designated by the reference numeral 18.

Considering initially the structure of first base 12, the base 12 can be seen to comprise an upper portion 22 which is contoured generally in the shape of a head and a lower portion 24 which serves as a pedestal whereby the first base section may be supported by a suitable support means, e. g., a table or the like. Formed in first base section 12 is a longitudinally axially vertically extending bore 26. Bore 26 is in communication with a first counter-bore 28 which extends longitudinally axially vertically from the bottom or pedestal portion 24 of first base section 12 at least partially vertically therethrough. The upper end of counter-bore 28 defines a tapered shoulder 30, which tapered bore is defined by the taper of the leading edge of the drill tool used to form counter-bore 28. Similarly, there is formed adjacent the upper end of longitudinally vertically axially extending bore 26 a tapered counter-bore 32 which corresponds in shape to counter-bore 30.

Disposed within longitudinally vertically extending bore 26 is a base rod 34. Base rod 34 is secured within bore 26 by a first tapered washer 36 which is press fitted onto rod 34 and shaped to conform to the conical taper of counter-bore 30. Rod 34 is secured at its upper end by a second tapered washer 37 which is press fit onto base rod 34 and which is shaped to conform to the taper of tapered counter-bore 32. The outside diameter of base rod 34 is substantially equal to the inside diameter of longitudinally vertically axially extending bore 26 and this, in cooperation with the effect of first tapered washer 36 and second tapered washer 37 with counter-bores 30 and 32 provides for the rigid disposition of base rod 34 within longitudinally vertically axially extending bore 26.

Formed in base rod 34 and extending longitudinally axially from the upper end thereof is a bore 38 which extends partially through base rod 34. As will be discussed below in detail, bore 38 is provided to receive

the lower end of first elongated pin 18 so as to support second base 14 thereabove.

Considering now the structure of second base 14, second base 14 comprises a member the upper surface of which is contoured to define the general shape of a head so as to provide a support surface for a wig or a hairpiece. The contour of the lower surface of second base member 14, may be any suitable shape desired by the designer and must only be sufficient to provide for a bore and top rod for being supported above first base 12 in a manner discussed below in detail. Formed in second base 14 is a longitudinally vertically axially extending bore 40. Bore 40 is provided at its upper end with a tapered counter-bore 42 and at its lower end with a tapered counter-bore 44. Counter-bores 42 and 44 are provided to accommodate the reception therein of tapered washers 46 and 48 respectively.

Disposed within longitudinally vertically axially extending bore 40 is a top rod 50 which is rigidly secured within bore 40 by tapered washers 46 and 48 which are press fit thereon in a manner generally known to those skilled in these arts.

Formed in the lower portion of top rod 50 is a first bore 52. Bore 52 extends longitudinally axially through a portion of top rod 50. Similarly, formed in the upper portion of top rod 50 is a longitudinally axially extending bore 54. Bores 52 and 54 are coaxial and of a depth which is such as to preclude their communication.

As is evident from FIGS. 2 and 3b, elongated pin 18 is provided on its upper end with a frusto-conically tapered surface 56. In this regard, the tapered surface of second bore 52 in top rod 50 is shaped to conform to the frusto-conical surface 56 of elongated pin 18. As may be best seen in FIG. 2, the assembly of first and second bases 12 and 14, respectively, is achieved by slidably positioning the lower end of first elongated pin 18 within axially extending bore 38 and the upper conically tapered surface 56 of elongated pin 18 within the frusto-conically tapered first bore 52 of top rod 50. The machining of these parts is such as to provide a relatively firm friction fit therebetween so that the elements are rigidly secured when the parts are assembled but can be disassembled merely by a slight twisting and the exerting of a separating force.

Considering therefore the assembly of the apparatus of FIGS. 2 and 3, first base member 12 and second base member 14 may be formed by many manufacturing procedures known generally to those skilled in this art. Particularly, bases 12 and 14 may be manufactured of plastic materials and molded or otherwise manufactured of materials in manners known generally to those skilled in these arts.

Thereafter, once the basic shape of the bases are formed, and considering initially first base 12, longitudinally vertically axially extending bore 26 is formed in conventional manner and thereafter counter-bore 28 and therewith counter-bore 30 as well as counter-bore 32 are formed therein. Base rod 34 is preformed and drilled to define axially extending bore 38 and is provided with first tapered washer 36 thereon which may be secured thereto by press fitting or shrink fitting or like manufacturing processes. With first tapered washer 36 disposed on the lower end of base rod 34, base rod 34 is slidably received within longitudinally vertically extending bore 26 until the tapered surface of first washer 36 is in engagement with the tapered surface of counter-bore 30. Thereafter, second tapered washer 37

is rigidly secured to the upper end of base rod 34 by press fitting, shrink fitting or the like and petitioned such as to provide that the tapered surface of tapered washer 37 is in surface to surface engagement with the tapered surface of counter-bore 32. With the parts assembled in this manner, base rod 34 is rigidly secured within longitudinally vertically axially extending bore 26.

With second base member 14 assembled by molding 10 or like processes, longitudinally axially extending bore 40 is formed therein by conventional bore forming means such as drilling or the like. Thereafter, and with top rod 50 formed such as to have a first axially extending tapered bore 52 in its lower end and a second bore 15 54 in its upper end, top rod 50 is provided at its lower end with a second tapered washer 48 which may be press fit or shrink fit in the same manner as washers 36 and 37 are provided on base rod 34. With second tapered washer 48 positioned on top rod 50, top rod 50 is disposed within axially extending bore 40 in second base member 14 in such a manner as to engage the tapered conical surface of second tapered washer 48 with the conical surface of tapered counter bore 44. With top rod 50 so disposed, the first tapered washer 46 is secured thereto by press fitting or shrink fitting in such a manner as to cause the engagement of the tapered conical surface of first tapered washer 46 with the tapered conical surface of tapered counter-bore 42. At this stage, the assembly of first base member 12 and second base member 14 is complete.

Ignoring for the moment the positioning of a member to be supported, e. g., a wig or hairpiece, second base member 14 is disposed above first base member 12 by the provision of an elongated pin 18 such as to place 35 the base of the pin within the longitudinally axially extending bore 38 in base rod 34 and its tapered conical surface 56 within the tapered conical first counter-bore 52 of top rod 50.

When it is desired to support a wig or hairpiece on 40 the members, pin 18 is positioned within an axially extending bore 38 in base rod 34 and the wig is positioned over pin 18 in such a manner as to cause the upper tapered conical end of pin 18 to pierce the interstices of the wig. With a wig or hairpiece so positioned on the upper surface of first base member 12, second base member 14 is positioned such as to receive the upper tapered conical surface 56 of elongated pin 18 within conical counter-bore 52 and thereafter a second wig or hairpiece may be positioned on and supported by second base member 14.

It may be noted that the upper surface of first and second base members may be called "crown pieces" in the wig industries. However, for purposes of the present disclosure they have been designated bases because the present invention may be utilized as a support means for supporting any member in spaced relationship wherein it is necessary to avoid the occurrence of contact of the surface of the supported member with adjacent surfaces.

Although it will be recognized that the foregoing detailed description has been with respect to a single embodiment of support means and with respect to the support of wigs or hairpieces, the utilization of the invention for purposes of supporting other structures wherein the piercing of the structure to be supported is permitted will be recognized by those skilled in the art. Further, it will be recognized that various structural

modifications can be made without departing from the scope of the invention. Specifically, the pedestal portion can be supported on a stand or by a wall bracket where desired, the structure of the pin 18 and its cooperation with bores 38 and 52 can be modified by shaping or the provision of washers such as to preclude relative rotational movement between the members, and set screws can be utilized to positively lock the pin in position within its respective bores.

Accordingly, it is considered to be manifest that many variations and modifications to the present invention as disclosed in detail may be made without departing from the spirit and scope thereof.

I claim:

1. Apparatus for supporting a plurality of members in spaced relation, comprising:
 a first base for supporting a member;
 bore means formed in said first base;
 at least a second base for supporting a member;
 a longitudinally extending bore formed in said second base;
 elongated pin means having a first end and a second end, said first end for being slidably received within said bore means in said first base, said second end being frusto-conically tapered, said elongated pin for being passed through a member being sup-

5

ported and for positioning said first and second bases in spaced relation; and
 a top rod rigidly disposed within said longitudinally axially extending bore in said second base, said top rod comprising a generally cylindrical element having a longitudinally axially extending counterbore disposed therein, said counterbore being frusto-conically tapered such as to conform to the taper of said frusto-conical taper of said elongated pin means and wherein said frusto-conically tapered elongated pin means is received within said frusto-conically tapered bore in said top rod.

2. Apparatus according to claim 1 and further including a second bore formed within said top rod, said second bore being longitudinally axially extending and coaxially extending with said first bore, said second bore being adapted to receive a second elongated pin means.

3. Apparatus according to claim 2 wherein said base rod and said top rod are rigidly secured within said bores in said first and second base members, respectively, by tapered washers rigidly secured thereto, said tapered washers for cooperating with frusto-conically formed counter-bores disposed within said bores in said first and second base members.
